DESIGN FOR A BANK MONEY ORDER FORM

John G. Mengel, Alexandria, Va., assignor to
General Money Order System, Inc., Harrisburg,
Pa., a corporation of Pennsylvania

Application September 18, 1941, Serial No. 103,403

Term of patent 7 years

To all whom it may concern:

Be it known that I, John G. Mengel, a citizen of the United States, residing at Alexandria, in the State of Virginia, have invented a new, original, and ornamental Design for Bank Money Order Forms, of which the following is a specification, reference being had to the accompanying drawing, forming part thereof.

The figure is a face view of a bank money order form embodying my novel design.

I claim:

The ornamental design for a bank money order form, as shown.

JOHN G. MENGEI.
